(57) **CLAIM**

I claim the ornamental design for the gemstone setting, as shown and described.

DESCRIPTION

FIG. 1 is a top view of the gemstone setting;
FIG. 2 is a front view of the gemstone setting;
FIG. 3 is a side view of the gemstone setting;
FIG. 4 is a perspective view of the gemstone setting; and,
FIG. 5 is a perspective view of the gemstone setting.
The broken lines shown in the drawings represent environmental matter and form no part of the claimed design.

1 Claim, 5 Drawing Sheets
